Primary Examiner — Karen E Kearney*Assistant Examiner* — Kristin E Reed(74) *Attorney, Agent, or Firm* — Polson Intellectual Property Law, PC; Margaret Polson**CLAIM**

The ornamental design for a band of a smart watch, as shown and described.

DESCRIPTION

FIG. 1 is a top, left side isometric view of a band of a smart watch showing our new design.

FIG. 2 is a bottom left side isometric view of FIG. 1.

FIG. 3 is a top side plan view of FIG. 1.

FIG. 4 is a bottom side plan view of FIG. 1.

FIG. 5 is a left side elevation view of FIG. 1.

FIG. 6 is a right side elevation view of FIG. 1.

FIG. 7 is a front side elevation view of FIG. 1; and,

FIG. 8 is a back side elevation view of FIG. 1.

The broken lines shown in the drawings depict portions of the band of a smart watch that form no part of the claimed design. The dash dot dash lines illustrate the bounds of the claim and form no part of the claimed design.
